CLAIM

I claim the ornamental design for a handle for a garden tool, as shown and described.

DESCRIPTION

FIG. 1 is an oblique view of the invention;

FIG. 2 is a top view of the invention;

FIG. 3 is a bottom view of the invention;

FIG. 4 is a front view of the invention; and,

FIG. 5 is a side view of the invention.

The broken line showing of the garden tool is included for the purpose of illustrating portions of the article and forms no part of the claimed design.
